UNITED STATES PATENT OFFICE.

JOSEPH B. MILTON, OF ENID, OKLAHOMA.

GRAVITY LOCK.

Application filed September 2, 1921. Serial No. 497,919.

To all whom it may concern:

Be it known that I, JOSEPH B. MILTON, a citizen of the United States, residing at Enid, in the county of Garfield and State 5 of Oklahoma, have invented new and useful Improvements in Gravity Locks, of which the following is a specification.

This invention relates to locking means for railway switches, the general object of 10 the invention being to provide positive means for locking the switch operating parts with the switch in either open or closed position and to so construct the parts that the key cannot be withdrawn from the lock, unless 15 the parts are in locked position, so that the switchman will know that the parts are not properly set from the fact that he cannot withdraw the key.

Another object of the invention is to, so 20 form the lock that it will be weather proof so that the switch can be actuated at all times irrespective of climatic conditions.

This invention also consists in certain other features of construction and in the 25 combination and arrangement of the several parts, to be hereinafter fully described, illustrated in the accompanying drawings and specifically pointed out in the appended claim.

30 In describing my invention in detail, reference will be had to the accompanying drawings wherein like characters denote like or corresponding parts throughout the several views, and in which:—

35 Figure 1 is an elevation showing the invention in use.

Figure 2 is a plan view.

Figure 3 is a longitudinal sectional view.

40 Figure 4 is a section on line 4—4 of Figure 3.

Figure 5 is a detail view showing the means for preventing withdrawal of the key.

45 Figures 6 and 7 are views showing the application of the invention to a different form of switch operating means.

In these views 1 indicates the switch stand which supports the rocking member 2 which is connected with the switch actuating means by the shaft 3 and with the indicating means 50 4 by the shaft 5. This member 2 is rocked manually by means of the hand lever 6 which is pivoted to the member at 7. The top of the stand is provided with notches 8 to receive the hand lever 6 when the parts have

been moved to actuate the switch to either 55 fully open position or fully closed position. Locking means have been provided for holding the parts with the switch in either open or closed position but such means will permit the parts to be moved to position 60 with the switch in an intermediate position so that there is danger of wrecking a train passing over the switch and it is the object of my invention to so form the locking means that the key cannot be withdrawn 65 from the lock until the hand lever is placed in one of the notches, thus indicating to the switchman that the parts have not been properly set and also serving as a means of identification of the switchman failing to 70 properly set the parts for unless he had the parts properly set he could not withdraw his key and this key will serve to identify him.

In carrying out my invention I form a 75 lock casing 9 on the member 2, this casing supporting the shaft 5 and having a slot in its lower end for receiving the upper end of the hand lever 6. A tumbler 10 is pivoted in the casing, as at 11, and this tumbler engages the end of the hand lever by means of the spring 12 so as to hold said lever in the notches. The tumbler is provided with the curved lower edge 13 which is adapted to be engaged by the end of the lever, when the same is being moved into either one of the notches, so that this movement will raise the tumbler to permit the lever to enter the notch and then the spring 12 will force the tumbler into locking engagement with the lever. The case 9 is provided with the key hole 14 for receiving the actuating key and the tumbler is provided with an arc shaped part 15 for receiving the bit of the key, these parts being so arranged that when the key is turned the bit engaging this curved part will tilt the tumbler on its pivot and raise it against the action of its spring and out of engagement with the hand lever, thus permitting the hand lever to be withdrawn from the notch. In order to prevent the withdrawal of the key unless the tumbler is in locking position I provide a lip 16 on the tumbler which will move across the bit receiving part of the key hole when the tumbler is in raised position and this lip will engage the bit of the key and prevent the withdrawal of the key from the lock if an 100 105

attempt is made to do so with the tumbler in a position other than its locking position. As before stated this will indicate to the switchman that the hand lever is in engagement with the notch and if he should leave the parts in unlocked position the key will identify him as the person at fault.

As will be seen the case is so formed as to prevent the entrance of rain or snow into the same so that the parts will operate under all climatical conditions and an angle plate 17 is secured to the hand lever to engage the button of the top of the switch stand when said hand lever is occupying a notch. This plate prevents an article from being passed into the lock casing to raise the tumbler. This will prevent an unauthorized person from moving the switch parts without a key.

Figures 6 and 7 show the invention applied to the oscillating type of switch lever, said lever being shown at 18. This lever 18 is held against movement by the right angular extension 19 on the hand lever 6' which is pivoted to the top of the casing 9' and extends through slots formed in the walls of the casing. The lever 6' is engaged by the tumbler 10'. The rest of the device is similar to that before described and the operation is substantially the same so that it is not thought necessary to describe this modification further.

It will of course be understood that the invention can be applied to any form of switch stand and the key used may be of the type of switch key now in use upon a number of railroads.

Attention is called to the simple nature of the locking means and also to the fact that the lock casing can be placed on the operating means now in use and which includes a locking member similar to the member 2 shown on the drawings. Thus the invention can be applied to existing types of switch operating means with but little change to such means so that the application of the

invention can be made with but little expense and without necessitating the use of a new type of key.

It is thought from the foregoing description that the advantages and novel features 50 of my invention will be readily apparent.

I desire it to be understood that I may make changes in the construction and in the combination and arrangement of the several parts, provided that such changes fall with- 55 in the scope of the appended claim.

What I claim is:—

In combination with a switch stand having a notched top and a rocking member therefore carrying an indicator through the 60 medium of a shaft, of a hand lever pivotally secured to said rocking member and adapted to control the lateral movement thereof, a weather proof lock casing provided with a slot in the lower end thereof to receive the 65 upper end of said hand lever and being designed to rest upon the top surface of the rocking member, a tumbler pivotally mounted adjacent one end thereof within the casing and designed to engage the upper end 70 surface of the hand lever when said lever is arranged in one of said notches, a spring having one end secured to the upper end of the casing and its free end bearing against the upper surface of said tumbler to hold 75 said lever in a locked position, said tumbler being provided with a portion of one edge curved, said portion being adapted to engage the end of said lever when it is being moved into either of said notches, a lip provided 80 on said tumbler adjacent the pivoted end thereof and being adapted to overhang an arc-shaped portion formed thereon as and for the purpose specified, and an angle plate secured to said lever and adapted to provide a pick proof cover when said lever is in a locked position.

In testimony whereof I affix my signature.

JOSEPH B. MILTON.
